WHIP STOCK

Odie B. Trotter, Houma, La.

Application May 19, 1937, Serial No. 143,409

8 Claims. (Cl. 255—1)

This invention relates to a device for controlling the direction of bore holes and more particularly to a whipstock for use in straightening or changing the direction in which an oil well is being drilled. The principal objects of the invention are to provide a whipstock with means for increasing the angle of deviation over that commonly obtained and to provide means for cleaning the hole where the whipstock is to be set.

10 In carrying out the invention, a whipstock is formed of two sections hinged together by means of a knuckle joint, the bottom of the lower section being provided with a sharpened or wedge-shaped end at its forward face so that when the whipstock reaches the bottom of the hole the sharpened end will penetrate the formation causing the lower section to swing slightly forward about the knuckle joint. Thus, the angle of the deviation of the line which the bit is to follow will be increased over what it would be if the whipstock were in one piece. A longitudinal passage is provided through both sections, and the upper end of this passage is connected to the interior of the drill stem so that while the whipstock is being lowered the drilling fluid may pass downwardly through and out at the bottom of the whipstock so as to remove any detritus which may have collected in the hole below the whipstock. A valve in the drill bit or collar closes the opening to the passage in the whipstock as soon as the whipstock is in place and the bit begins to move down the whipstock face. All of the drilling fluid is then forced out through the bit as is customary in rotary drilling practice.

35 For a better understanding of the invention reference may be had to the accompanying drawing in which

Figure 1 is a vertical elevation of the whipstock ready to be lowered in the hole;

40 Figure 2 is a vertical sectional elevation through the upper end of the whipstock showing the bit and the valve for controlling the flow of the drilling fluid;

45 Figure 3 is a section taken on the line 3—3 of Figure 2 looking in the direction of the arrows;

Figure 4 is a vertical section through the knuckle joint, while

50 Figure 5 is a partial vertical section of a slightly modified form of the attaching means and the valve.

Referring to the drawing, a whipstock is illustrated as comprising an upper section 10 and a lower section 12, each of these sections being tapered with the thinner end uppermost and with 55 the face 13 slightly concave as shown in Figure 3,

to accommodate the drill bit. The upper section 10 is provided with a ring 14 adapted to engage a drill collar 16 as by means of a left hand threaded connection 18. The drill collar is of course secured to the lower end of the drill stem or string 5 in any suitable manner. The two sections of the whipstock are hinged together as by means of the knuckle joint 20 shown in Figures 1 and 4. This joint comprises a round projection on the upper end of the lower section and a similarly 10 shaped groove or socket in the lower end of the upper section. When the backs of the two sections are aligned, as shown in heavy lines in Figure 1, a slight space 22 will exist in front of the joint 20 to allow for a limited movement of the 15 lower section with respect to the upper section.

The lower end of the lower section is provided with a sharpened or wedge-shaped projection 24 at the front or face side of the whipstock. When the whipstock is hanging freely from the 20 drill collar the lower section 12 will be in substantial alignment with the upper section 10 as shown in full lines in Figure 1. However, when the lower end of the whipstock reaches the bottom of the hole the projection 24 will engage the 25 formation, and because of the shape of this projection the further lowering of the whipstock will cause the lower section to move forward to the position shown in dotted lines. If it is assumed that the angle by which the whipstock is tapered 30 is of the order of $2\frac{1}{2}^{\circ}$ this angle can be doubled to 5° when the lower section has moved to its forward position and the whipstock will thus be 35 doubly effective in straightening or changing the direction of the hole.

The whipstock sections 10 and 12 are preferably formed of a non-magnetic metal so that the device can be oriented in the hole through the use of one of the usual well surveying instruments, the movable magnetic needle or member of which 40 would otherwise be deflected by magnetic metal in the whipstock.

When lowering a whipstock near to the bottom of a bore hole, it is desirable to clean that portion of the hole below the whipstock so that the 45 device will have a firm foundation in the hole. To this end, the upper and lower sections of the whipstock are provided respectively with longitudinal passages 26 and 28, these passages being in end to end alignment at the knuckle joint 50 20 and the adjacent ends of the passages being slightly flared, as shown more clearly in Figure 4, so that the drilling fluid can pass through the whipstock in uninterrupted flow even though the two sections may be slightly out of line, as shown 55

in the dotted lines of Figure 1. The drill collar 16 is also provided with a passage 30 connecting with the usual opening in the drill pipe, not shown. The drill bit 32 which is attached to the 5 drill collar 16 by means of the right hand threaded connection 34 is also provided with a longitudinal passage 36 opening at the bottom of the bit so that part or all of the drilling fluid passing downwardly through the drill stem and the passage 30 will pass outwardly ahead of the bit to remove detritus in the hole in the usual manner. The drill collar 16 is provided with an opening 38 connecting the passage 30 with the upper end of the passage 26 in the whipstock and this opening 15 has an enlarged space 40 for accommodating a ball valve 42. A plug 44 threaded into the drill collar serves as a valve seat for the ball 42 but in the position shown in the drawing the ball is held away from the seat 44 by means of a pin 20 46 secured to the whipstock directly across the upper end of the passage 26. In operation, when it is desired to change the direction of a hole, the bit 32 is attached to the drill collar 16 by means of the right hand threaded connection 34 and the 25 drill collar is then screwed into the ring member 14 after which the drill collar is attached to the lower end of the drill stem in the usual manner. In this position, as illustrated more clearly in Figure 2, the ball 42 will be held away from its 30 seat 44 by means of the pin 46 and as the whipstock is lowered nearly to the bottom of the hole part of the drilling fluid which is then pumped downwardly through the passage 30 will pass through the opening 38 and downwardly through 35 the passages 26 and 28 and out at the bottom of the whipstock where it serves to wash away any detritus which may have collected in the hole. The whipstock is then set on the bottom of the hole by the weight of the drill pipe and the projection 40 24 will penetrate the formation so as to move the lower section 12 forwardly about the knuckle joint 20 to increase the effective deviation of the device.

The drill pipe is then turned in a clockwise 45 direction which causes the unthreading of the left hand connection 18 and the bit 32 is then rotated down the face 13 of the whipstock. As soon as the drill collar 16 is disengaged from the whipstock ring 14 the valve 42 will seat, closing the 50 passage 38 and causing all of the drilling fluid to pass through the drill bit. When it is desired to remove the whipstock, the drill stem is pulled upwardly until it strikes the ring 14 and then turned in a counterclockwise direction to take up 55 the left hand connection 18 after which the whipstock may be pulled out of the hole.

In Figure 5 is shown a slightly modified form in which a drill bit 48 is shown connected directly to the drill stem 50 by the usual right hand threaded connection 52. The bit is provided with an enlarged shank 54 adapted to be connected to the whipstock collar 56 by means of a left hand threaded connection 58. The shank of the bit is provided with passages 60 and 62 corresponding to passages 30 and 38 in the form disclosed in Figure 2 and a ball valve 64 cooperates with its seat 66 and an unseating pin 68 in the same manner described with reference to the form shown in Figures 1 through 4. In the form 65 shown in Figure 5 the operation is similar to that already disclosed, a clockwise rotation of the drill stem causing the disengagement of the left hand threaded connection 58 so that the drill bit can travel down along the face of the whipstock. 70

75 Obviously many modifications and variations

of this invention may be made without departing from the spirit and scope thereof, and therefore only such limitations should be imposed as are indicated by the appended claims.

I claim:

5 1. A whipstock comprising an upper tapered section and a lower tapered section, a hinged joint between said sections, said lower section being provided at its bottom forward end with a wedge-shaped projection, the arrangement being 10 such that the projection will tend to penetrate the formation at the bottom of a hole so as to move the lower section forward about said hinged joint to increase the angle of deviation.

15 2. A whipstock comprising an upper section 15 and a lower section, each section having an inclined face and being formed of non-magnetic metal, a knuckle joint between said sections and arranged so that the lower section may be moved laterally in the direction of said face, said lower 20 section being provided with a chisel-like projection extending downwardly from the bottom of said lower section and in substantial alignment with said inclined face, said projection adapted to penetrate the formation being drilled to cause 25 the lower section to move about said knuckle joint so as to increase the angle of deviation of said face.

30 3. A whipstock for controlling the deviation of a well being drilled comprising a longitudinally 30 tapered portion, a ring formed at the upper end of said tapered portion, a longitudinal passage extending downwardly through said tapered portion with an outlet opening at the bottom thereof, a drill stem extending downwardly through said 35 ring, a bit secured to said drill stem, means on said drill stem for cooperating with said ring to support said tapered portion while the whipstock is being lowered into the well, said drill stem and bit being provided with a passage for conducting 40 drilling fluid into the well below the bit, and said drill stem being provided with a conduit connecting the passage in the drill stem with the passage in said tapered portion, the arrangement being such that part of the drilling fluid will pass 45 from the stem in to and downwardly through said tapered portion so as to remove detritus from the well below the whipstock.

4. A whipstock for controlling the deviation of a well being drilled comprising a longitudinally 50 tapered portion, a ring formed at the upper end of said tapered portion, a longitudinal passage extending downwardly through said tapered portion with an outlet opening at the bottom thereof, a drill stem extending downwardly through said 55 ring, a bit secured to said drill stem, means on said drill stem for cooperating with said ring to support said tapered portion while the whipstock is being lowered into the well, said drill stem and bit being provided with a passage for conducting 60 drilling fluid into the well below the bit and said drill stem being provided with a conduit connecting the passage in the drill stem with the passage in said tapered portion, a valve in said conduit normally closed by the pressure of the 65 drilling fluid while the bit is being rotated to drill the hole, and means for holding said valve open while the whipstock is being lowered so that part of the drilling fluid will pass downwardly through and out at the bottom of the whipstock. 70

5. A whipstock for controlling the deviation of a hole being drilled, a longitudinal passage extending downwardly through and having an outlet at the lower end of said whipstock, a drill stem, a drill collar on said stem, a bit secured 75

to said drill collar, means for supporting said whipstock from said collar while being lowered into the well, said drill stem, collar and bit being provided with a passage for conducting drilling fluid downwardly and out into the hole below said bit, a conduit in said drill collar connecting the passage in said collar with the passage in said whipstock, a valve in said conduit adapted to be closed during drilling operations of the bit, and means for holding said valve open while the whipstock is being lowered in the hole.

6. A whipstock comprising an upper section and a lower section, said sections being formed of non-magnetic metal, a hinged joint between 15 said sections, said lower section being provided at its bottom forward end with a wedge-shaped projection, the arrangement being such that as the whipstock is lowered the projection will tend to penetrate the formation and to move the lower 20 section forward about said hinged joint so as to increase the angle of deviation, said upper and lower sections being provided with substantially aligned longitudinal passages for conducting drilling fluid downwardly through said whipstock 25 as the latter is being lowered into a well, said passages being connected in end to end relation through said hinged joint.

7. A whipstock for controlling the direction of a drill bit secured to a drill stem, comprising a 30 longitudinally tapered portion, a ring at the upper end of said tapered portion, a threaded connection between said ring and said bit, a passage

extending downwardly through said drill stem and bit, a second passage extending downwardly through said tapered portion, a conduit in said bit connecting said first mentioned passage with said 5 second passage, a check valve adapted to close said conduit when said bit and collar are disjoined and means for rendering said valve inoperative when said bit and said ring are in threaded connection.

8. A whipstock for controlling the direction of a drill bit secured to a drill collar by a right hand threaded connection, comprising a longitudinally tapered portion, a ring at the upper end of said tapered portion, a left hand threaded connection between said ring and said collar, a passage extending downwardly through said drill collar and bit, a second passage extending downwardly through and having an outlet at the bottom of said tapered portion, a conduit in said 20 collar connecting said first mentioned passage with said second passage, a check valve adapted to close said conduit when said collar and ring are disjoined and means for rendering said valve 25 inoperative when said collar and said ring are in threaded connection, said means including a pin disposed across the opening of said second passage adjacent said conduit and adapted to hold said check valve open when said collar and ring are in threaded connection. 30
